Mr Wallace White
ATTY.

UNITED STATES PATENT OFFICE.

WICTOR OSKAR JULIUS ANDERSSON, OF MALMO, SWEDEN.

CALCULATING-MACHINE.

1,381,898.

Specification of Letters Patent. Patented June 21, 1921.

Application filed June 3, 1919. Serial No. 301,533.

To all whom it may concern:

Be it known that I, WICTOR OSKAR JULIUS ANDERSSON, a subject of the King of Sweden, residing at Malmö, in the county of Malmöhus and Kingdom of Sweden, have invented new and useful Improvements in Calculating-Machines, of which the following is a specification.

My invention relates to improvements in calculating machines, such for instance, as that shown and described in Letters Patent of the United States No. 1,160,015, granted to Franz Trinks, under date of November 9, 1915, in which calculations are performed by means of setting disks having adjustable teeth or toothed wheels which transmit the values represented by said teeth to a registering or counting mechanism. And more particularly the invention relates to improvements in calculating machines of this class in which a mechanism for counting the revolutions of the crank is provided, which mechanism preferably arranged coaxially with the registering mechanism is operated by means of a pin rotating together with the setting disks and coöperating with one of the gear wheels in the revolutions counting mechanism by every revolution of the crank.

In case of division the dividend is first set into the setting disks and transmitted to the main registering mechanism by a revolution of the crank in the + direction, as is usual in machines of this class. Now the dividend is removed from the setting mechanism and replaced by the divisor. Meanwhile after the single revolution of the crank the revolutions counting mechanism indicates the number "1," which must be reset before the division in order to avoid a wrong quotient.

The object of my invention is to avoid this special operation of resetting the revolutions counting mechanism and for that reason I have arranged the pin that at each revolution of the crank coöperates with the respective gear wheel in the revolutions counting mechanism swingable in a direction transversely of the gear wheels and provided means for manually operating the pin from outside of the machine casing.

For the purpose of explaining the invention one embodiment thereof has been illustrated in the accompanying drawings, in which the same numerals of reference have been used in all the views to indicate corresponding parts.

In said drawing—Figure 1, is a vertical cross section of a machine embodying the invention, Fig. 2, is a plan view of the mechanism and partly in horizontal section illustrating the said pin in meshing position and Fig. 3, is a plan view similar to that shown in Fig. 2 and illustrating the pin in disengaged position.

In the drawing, 1 indicates the setting wheels carried on the shaft 2 and secured thereto. The shaft 2 also carries at one end thereof the usual gear wheel 3 secured to the shaft 2 and meshing with a gear wheel 5 mounted on a shaft 4. The gear wheel 5 is provided with a pin 7 swingably mounted on a pivot 6 in the gear wheel and adapted when in normal position to mesh with the gear wheel 8 in the revolutions counting mechanism in the usual way. The pin 7 is intended to be held in normal position by means of a little spring 13. As usual a plurality of gear wheels each secured to a numeral wheel are provided in the revolutions counting mechanism, however, only one gear wheel and one numeral wheel are illustrated for the sake of simplicity. At the outside of the side wall 9 there is secured a spring arm 10, whose free end 11 is bent inward through an opening in the side wall 9 of the machine casing and wedge shaped.

When the arm 10 normally held in the position illustrated in Fig. 2 is manually depressed inward, the pin 7 will strike one of the inclined surfaces 12 (only one surface shown on the drawing) of the wedge 11 by rotation of the gear wheel 5 and will thereby swing out of meshing position. As soon as the dividend has been transmitted from the setting wheels into the main register the arm 10 is released, so that the pin will be able to return to its normal position into mesh with the gear wheel 8 by the next rotation of the setting mechanism.

I wish it to be understood, that this embodiment has been shown merely for the purpose of explaining the invention and that various changes may be made in the general arrangement and construction within the gist of my invention.

I claim herein as my invention:

1. In a calculating machine, the combination with a setting mechanism including disks, mechanism adapted to receive a value transmitted from the setting mechanism, a revolutions counting mechanism comprising numeral wheels and gear wheels and adapt-

ed for counting the revolutions of the crank operating the setting mechanism, of a pin rotating together with the setting disks and normally meshing with one of the 5 gear wheels in the revolutions counting mechanism at every revolution of the crank, said pin being swingable in a direction transversely of the last mentioned gear wheels, and means for operating said pin 10 from outside of the machine casing.

2. In a calculating machine, the combination with a setting mechanism including disks, mechanism adapted to receive a value transmitted from the setting mechanism, a 15 revolutions counting mechanism comprising numeral wheels and gear wheels, and adapted for counting the revolutions of the crank operating the setting mechanism, of a pin rotating together with the setting disks and normally meshing with one of the gear 20 wheels in the revolutions counting mechanism at every revolution of the crank, said pin being swingable in a direction transversely of the last mentioned gear wheels, and a movable arm secured to a fixed part 25 of the machine and adapted to be manually pressed and thereby to swing the pin out of meshing position.

3. In a calculating machine, the combination with a setting mechanism including 30 disks, mechanism adapted to receive a value transmitted from the setting mechanism, a revolutions counting mechanism comprising numeral wheels and gear wheels, and adapted 35 for counting the revolutions of the crank operating the setting mechanism, of a pin rotating together with the setting disks and normally meshing with one of the gear 40 wheels in the revolutions counting mechanism at every revolution of the crank, said pin being swingable in a direction transversely of the last mentioned gear wheels, and a movable arm secured to a fixed part 45 of the machine and provided with a wedge adapted to be carried into the path of the pin by manual pressing said arm thereby to effect the swinging of the pin out of meshing position when the pin during its motion strikes one of the inclined surfaces of the 50 wedge.

In testimony whereof I have signed my name to this specification.

WICTOR OSKAR JULIUS ANDERSSON.
